Primary Examiner — Mojtaba Tehrani(74) Attorney, Agent, or Firm — Jose Cherson Weissbrot(57) CLAIM

The ornamental design for a golf net, as shown and described.

DESCRIPTION

FIG. 1 is a front perspective view of a golf net, showing my new design; and,

FIG. 2 is a front elevation view thereof.

The broken line in the drawings depicts unclaimed portions of the golf net only and forms no part of the claimed design.

1 Claim, 2 Drawing Sheets(56)
